UNITED STATES PATENT OFFICE.

ELIJAH A. OVENSHIRE, OF LOS ANGELES, CALIFORNIA.

PRINTING-MACHINE.

977,830.

Specification of Letters Patent.

Patented Dec. 6, 1910.

Application filed June 29, 1909. Serial No. 505,080.

To all whom it may concern:

Be it known that I, ELIJAH A. OVENSHIRE, a citizen of the United States, residing at Los Angeles, in the county of Los Angeles 5 and State of California, have invented a new and useful Printing-Machine, of which the following is a specification.

This invention relates to a machine adapted for printing on a continuous strip and is 10 adapted for printing a tape or for embossing or printing tickets, or color work, or, in fact, any printing which is to be applied to a strip or ribbon.

One of the main objects of the invention is 15 to provide for automatically feeding the strip being printed and imprint thereon impressions from different forms or plates. Thus, the machine may be provided with a plurality of forms or plates which will 20 be automatically impressed in succession against the strip, so that it is possible to print a single strip from a series of different forms or plates and thereby produce a strip printed with a succession of different notices 25 or cards. If such forms or plates are all identical with each other, the strip will be printed with a succession of the same reading matter or other characters, while if the forms or plates are of different type or 30 character the strip will be provided with a series of impressions corresponding to the several different types or characters.

A further object is to provide for assembling such forms or plates in the machine in 35 a magazine, preferably in pack form, whereby the capacity of the machine is unlimited, that is to say, it will operate continuously and automatically to impress the plates in succession against the strip so long as there 40 are any plates in the magazine, so that the only manual operation required is to refill the magazine from time to time. Each plate after being impressed against the strip is discharged from the machine. The order in 45 which the plates are impressed upon the strip is determined by the order in which they are inserted in the magazine.

Referring to the drawings:—Figure 1 is a plan view of the machine. Fig. 2 is a 50 vertical section on line x^2-x^2 Fig. 1. Fig. 3 is a section on line x^3-x^3 Fig. 2. Fig. 4 is a section on line x^4-x^4 Fig. 2. Fig. 5 is a section on line x^5-x^5 Fig. 2. Fig. 6 is a section on line x^6-x^6 Fig. 2. Fig. 7 is a 55 section on line x^7-x^7 Fig. 2. Fig. 8 is a

plan view of the magazine and plate follower.

The machine comprises a table 1 supported by legs 2, the table being provided as shown in Fig. 1 with an extension 3 forming a magazine table.

4 designates the forms or plates which are supported on the magazine table as will be described and 5 is the strip or tape which is to be printed, the latter being caused to progress from right to left (Figs. 1 and 2) and the plates being fed forward with the line of movement at right angles to the line of progression of the strip, the plates being moved in succession underneath the strip 65 and being pressed up against the underside of the strip by a vertically operating platen 6, each plate being inked before it is moved under the strip. The strip remains stationary while the plate is impressed against 70 the strip by the platen 6 and after the impression has been made the strip moves forward and the plate is discharged from the machine and another plate takes its place on top of the platen, this operation being 75 repeated successively, the plates being moved one after the other underneath the strip and impressed against the strip and discharged from the machine and the strip being advanced intermittently after each 80 impression.

The strip 5 is fed from a roll 7 on a core 8, the latter being mounted on a shaft 9 which is supported in a pair of notched arms 10 which form part of a bracket 11 which is 90 bolted to the table 1. The roll 7 is prevented from turning ahead of the speed of the strip 5 by being slightly retarded frictionally by a pair of friction plates 12 which are adjustably secured on the shaft 9, as 95 shown in Fig. 1. From the roll 7 the strip 5 passes over a supporting roller 13, also mounted on the bracket 11, which roller is mounted on a shaft 14, the ends of which are journaled in studs 15 screwed in the 100 bracket 11 and provided with knurled heads for adjusting the bearings of the shaft 14.

A tension regulator is provided above the roller 13 and consists of a comb with spring teeth 16 which teeth rest upon the surface 105 of the strip 5, the comb 16 being supported by a cross bar 17. The pressure of the teeth 16 upon the strip 5 prevents the latter from being carried forward farther than it is actually pulled. As the strip 5 is advanced 110

intermittently it is necessarily jerked somewhat and without the tension device the jerk would be apt to move the strip farther than it is positively drawn by the actuating mechanism. From the roller 13 the strip 5 passes under a guide roll 18 supported by a frame 19, thence passes underneath a bed 20, thence under another roller 18, and thence to a guide roller 21 supported by studs 22 similar to the studs 15 and mounted in arms 23. From the roller 21 the strip 5 passes onto a receiving reel 24. Above the roller 21 is a strip holder so constructed as to press firmly against the strip immediately above the roller 21 and hold the strip against rearward movement during the recovery stroke of the strip actuating device to be described, and which automatically moves out of contact with the strip to permit the forward movement of the strip and not impede its movement during the forward stroke of the strip actuating device. This strip holder comprises a blade 25, in the lower edge of which is inserted a strip of padding 26 adapted to make contact with the strip 5, the blade 25 being secured to a frame 27 on a shaft 28 journaled in the arms 23.

One end of the shaft 28 has an arm 29 upon which a downward pull is exerted by a coil spring 30. At the other end of the shaft 28 is an arm 31 to which is connected a toggle lever 32. The toggle lever 32 is pivoted to a toggle lever 33 which is rigid on a shaft 34. An arm 35 projects from the shaft 34 and is connected with an operating rod 36, the upper end of which slides through a guide 37, the lower end of the rod 36 being forked and straddling the main shaft 38 which acts to guide the lower end of the rod 36. At an intermediate point on the rod 36 is a roller 39 which is in the path of movement of cam plates 40 and 41, which are arranged substantially diametrically opposite on a cam disk 42 mounted rigidly on shaft 38 and the cam 40 serves to act against the roller 39 to depress the rod 36 while the cam 41 serves to act against the underside of the roller 39 to elevate the rod 36. The cams 40 and 41 are so located on the disk 42 that the cam 41 lifts the rod 36 and flexes the toggle levers 32, 33 as shown by dotted lines in Fig. 2, thereby lifting the strip holder blade 25 from the strip 5 during the forward stroke of the strip actuating device, while advancing the strip. While, when the rod 36 is depressed by the cam 40, the strip holding blade 25 is moved down against the strip 5 and prevents the retraction thereof during the recovery stroke of the strip actuating device. It will be understood that the spring 30 serves to maintain the strip holding blade 25 elevated when the latter is not positively depressed by the cam 41 and the object of the cam 40 is to positively move the blade 25 down and into contact with the

strip 5, the spring 30 not being depended upon for such purpose. The toggle lever 32 has a heel 43 which permits the toggle levers 32 and 33 to be manually bent as indicated in dotted lines in Fig. 2, the heel 43 preventing further movement of the toggle levers. This function of the toggle levers permits them to be manually operated to lift the strip holding blade 25 at any time irrespective of the position of the parts of the machine when it is desired to free the strip 5 to enable it to be withdrawn or moved freely along in the machine. When the toggle levers 32 and 33 are so bent the spring 30 which exerts downward pull on the arm 31 holds the toggle levers in this position with the blade 25 raised until such time as the toggle levers are restored to their normal straight position. Thus, with this device it is possible to quickly release the strip 5 and it is not necessary to manually hold the blade 25 elevated as the toggle levers 32 and 33 and spring 30 perform that function.

The receiving reel 24 has a shaft 44, one end of which is mounted in a stub shaft 45 which is rotatably mounted in a trunnion 46, the latter being externally threaded and screwed in one of the arms 23. The inner end of the stub shaft has a flange 47 faced with rubber 48 which bears against the adjacent flange 49 of the reel 24. The flange 47 acts as a friction clutch to drive the reel 24 and the friction thereof is so regulated that while it is sufficient to drive the reel and pull the strip through the machine, each time the strip is arrested and held stationary by the strip holding blade 25, the flange 47 will slip while the reel 24 remains stationary. As shown in Fig. 7 the friction between the clutch 47 and flange 49 is secured by a spring 50 which, through the medium of a block 51 in which the other end of the shaft 44 is journaled, pushes the shaft 44 and reel 24 to the left against the friction clutch 47. The block 51 and spring 50 are contained within a trunnion 52 screwed in the outer arm 23. The block 51 has a headed stem 53 by means of which the block 51 may be retracted to enable the reel 24 to be freely spun around when desired to manually wind or unwind the strip on the reel without operating the machine. A grooved pulley 54 is carried on the stub shaft 45 and is continuously driven by a belt 55 which runs over idle pulleys 56 and a driving pulley 57 on shaft 38. Thus as the shaft 38 rotates continuously and through the belt 55 continuously rotates the clutch 47, the latter operates the reel 24 whenever the strip 5 is released by the strip holder and when the strip holder retains the strip 5 against movement, the clutch 47 slips without actuating the receiving reel 24.

The strip actuating device comprises a forked frame 58 which has an arm 59 with

a hub 60 mounted on a shaft 61 supported by brackets 62. The upper end of the forked frame 58 carries a roller 63, while a gripping blade 64 is slideable in the frame 58. The gripping blade 64 has lugs 65 to which is connected a link 66, the lower end of the latter being connected with a lug 67 on a hub 68 which is journaled on shaft 61 and is received in a slot 69 formed in the hub 60. The hub 68 has a lug 70 with a spherical head. The hub 60 has a lug 71 with spherical head. Projecting also from the hub 68 is an arm 72 having recesses 73, 74 which are adapted to be engaged by a spring pressed bolt 75 carried in the arm 59, and the bolt 75 serves to hold the hub 68 in either of two positions, *i. e.*, with the blade 64 in contact with the strip 5 or out of contact with the strip 5. A cam plate 76 on the disk 42 serves to operate against the stud 70 to depress the latter and move through the hub 68. Lug 67 and link 66 move the blade 64 out of contact with the strip 5, while a cam plate 77 on the disk 42 serves 25 to act against the lug 70 to rock the hub 68 in the other direction and move the blade 64 into contact with the strip 5. The plate 76 only momentarily contacts with the lug 70 but depresses the hub 68 sufficiently to cause 30 the recess 73 to be engaged by the bolt 75 so that when so engaged the blade 64 is held in contact with the strip 5, during the stroke of the frame 58, after the cam plate 76 has left the lug 70 until the lug 70 shall have 35 been acted upon and moved in the other direction by the plate 77 which releases the notch 73 from bolt 75 and link 66 releases blade 64 from the strip 5. Thus, the plates 77 and 76 serve to respectively kick the blade 64 40 into or out of contact with the strip 5 and the blade 64, after being so shifted, is detachably located in either of said positions during the remainder of the rotation of the disk 42. The frame 58 is oscillated by 45 means of a cam 78 mounted on the shaft 38 which acts against the lug 71 in a continuous manner, so that the frame 58 sweeps gradually forward and back. In Fig. 2, the frame 58 is shown in dotted lines at the beginning of its forward stroke with the blade 64 gripping the strip 5, so that as the frame 58 moves forward the strip 5 will be drawn forward with it, while the full lines indicate the frame 58 and other parts of the machine 55 at the position that they have immediately after the impression. When the frame 58 reaches the end of its outward stroke the cam plate 77 acts upon lug 70 through the described connections to release the blade 64 from the strip 5, so that the frame 58 can freely travel to the dotted line position without dragging the strip 5, the latter during this movement of the frame 58 being gripped by the strip holding blade 25. An 60 adjusting screw 79 is arranged in a cross 65

bar 80 against which screw the lug 71 strikes to limit the forward stroke of the frame 58. The frame 58 operates by gravity through its return stroke and is stopped at the end of its return stroke by an adjusting screw 70 75 80 85 90 95 100 105 110 115 120 125 130

81 in the arm 59, which screw strikes against the table 1, as shown in dotted lines in Fig. 2. The cam 78 is so cut that it will permit the frame 58 to fall by gravity farther than shown in dotted lines in Fig. 2 if the screw 81 be adjusted to permit of such further movement, hence by adjusting screw 79 to the right and adjusting cam 78 to the right on shaft 38 (Fig. 2) the cam 78 will then act to move the lug 71 farther and thus actuate the frame 58 farther to the left which, together with the adjustment of screw 81 to permit the farther movement of frame 58 to the right will result in causing the frame 58 to be actuated through a longer stroke and thereby shift the strip 5 accordingly.

The plates 4 are arranged in a pile one above the other in a magazine comprising four vertical angle bars 82 which extend 90 above the magazine table 3. Extending longitudinally of the magazine table 3 are ways 83 which guide a sliding plate follower 84, the latter having lugs 85 which receive the end of a rock arm 86. Extending laterally 95 from the rock arm 86 is a post 87 which is engaged by a notch 88 in a connecting rod 89 as shown in Figs. 3, 5 and 1. The front end of the connecting rod 89 is pivoted to a slotted rock lever 90 which is oscillated by 100 a crank pin 91 which projects from a cam 92 mounted on shaft 38 and as the arm 90 oscillates it acts through the connecting rod 89 and rock arm 86 to reciprocate the plate follower 84. The rear wall of the notch 88 105 in the connecting rod 89 is shallow as shown in Fig. 3 and a flat spring 93 bears against the underside of the post 87 and under ordinary conditions holds the notch 88 in engagement with the post 87. But if for any reason 110 the follower plate 84 should stick in moving forward, the spring 93 will yield and permit the connecting rod 89 to lift and disengage the notch 88 from post 87, so that while the connecting rod 89 will be positively 115 drawn forward the follower plate 84 will not travel forward but remains stationary without stopping the operation of the machine, thereby preventing possible damage which might occur otherwise.

The follower plate 84 is adapted to operate underneath the lower ends of the vertical angle bars 82 and push out the lowermost plate 4 in the magazine and thus during each forward stroke of the follower plate 84, the lowermost plate 4 is moved forward by the follower plate and deposited between undercut ways 6^a on the platen 6 directly underneath the strip 5 and bed 20. The ways 6^a hold the plate properly in alignment 130

and firmly against the platen. The platen 6 is mounted on a plunger 94 which is mounted to slide vertically in a guide 95 and is prevented from turning by a feather 96. 5 The plunger 94 is operated by a cam 97 on shaft 38 as shown in Fig. 5 and indicated in Fig. 2, the cam 97 being so timed as to lift the plunger 94 and raise the platen 6 and impress the plate 4 against the strip 5 while 10 the strip is stationary, the cam permitting the plunger 94 and platen 6 with plate 4 to drop immediately after the impression, immediately after which the gripping blade 64 carries the strip 5 forward the next step. 15 The frame 19 which supports the bed is adjustable by four screws 99. As each plate 4 is moved forward by the plate follower 84, the plate 4 passes underneath a pair of inking rollers 100 which ink the plate before it 20 is deposited on the platen 6. Each ink roller 100 is supported at each end by a post 101 which projects up through the table 1 and is slidably mounted therein. The lower ends of the posts 101 are secured to a plate 102 25 which is raised at intervals by a rock lever 103 having an adjusting screw 104, the lever 103 being operated by the cam 92 as shown in Fig. 3. The cam 92 allows the ink rollers 100 to drop so as to ink the plate 4 as it 30 passes thereunder, the cam 92 acting to raise the rollers 100 during the rest of the time against a distributing roller 105 which in turn receives ink from a roller 106, the latter receiving ink from a roller 107, the latter being automatically given longitudinal 35 movement by a lever 108 operated by a cam 109 driven by a belt 110 from grooved pulleys 111 on shaft 38, ink being furnished to the roller 107 by a plate 112. As each plate 40 4 is moved onto the platen 6 it pushes off the previous plate which has just made the impression and the plates 4 are thus moved one by one onto the platen 6, impressed against the strip 5 and discharged from the 45 machine, the strip 5 advancing during the interval between impressions and thus the strip 5 is printed with a series of impressions.

What I claim is:—

50 1. A bed, means for intermittently advancing a strip longitudinally and move the strip across the bed, ways extending laterally from the bed, a plate follower sliding along said ways, a platen movable toward and from the bed, the plate follower having a pair of vertical lugs, a pivoted rock arm, the end of which engages between said lugs, a connecting rod having a notch, means for operating said rod, a pin on said rock arm 55 engaging said notch, a flat spring on the connecting rod bearing against said pin and yieldingly holding the connecting rod in engagement with the pin, and means for reciprocating the connecting rod.

65 2. A bed, means for intermittently advancing a strip longitudinally and move the strip across the bed, ways extending laterally from the bed, a plate follower sliding along said ways, a platen movable toward and from the bed, the plate follower having a pair of vertical lugs, a pivoted rock arm, the end of which engages between said lugs, a connecting rod having a notch, a pin on said rock arm engaging said notch, a flat 70 spring on the connecting rod bearing against said pin and yieldingly holding the connecting rod in engagement with the pin, a slotted rock arm, a main shaft, a cam on the main shaft, and a crank pin carried by the cam and projecting into said slotted rock 75 arm, said connecting rod being connected to said slotted rock arm.

80 3. A bed, means for intermittently advancing a strip longitudinally and move the strip across the bed, a platen slideable toward and from the bed, a plurality of separate plates in a pack at one side of the bed, a follower plate for sliding said plates sequentially toward and away from said platen, a pair of inking rollers between said 85 pile of plates and said platen, vertical posts supporting said inking rollers, a horizontal plate supporting said posts, a lever extending under said plate, a shaft, and a cam thereon for rocking said lever to reciprocate 90 said posts and lift the ink rollers intermittently.

95 4. Means for intermittently advancing a strip longitudinally, a platen slideable toward and from the strip, a plurality of 100 separate plates in a pack at one side of the strip, a follower plate for sliding said plates sequentially toward and away from said platen, a pair of inking rollers between said 105 pile of plates and said platen, vertical posts supporting said inking rollers, a horizontal plate supporting said posts, a lever extending under said plate, a shaft, a cam thereon for rocking said lever to reciprocate said 110 posts and lift the ink rollers intermittently, and a distributing roller above said ink rollers for supplying ink thereto when the first 115 rollers are lifted.

120 5. Means for intermittently advancing a strip longitudinally, a platen slideable toward and from the strip, a plurality of separate plates in a pack at one side of the strip, a follower plate for sliding said plates sequentially toward and away from said platen, a pair of inking rollers between said 125 pile of plates and said platen, vertical posts supporting said inking rollers, a horizontal plate surrounding said posts, a lever extending under said plate, a shaft, a cam thereon for rocking said lever to reciprocate said posts and lift the ink rollers intermittently, a distributing roller above said ink rollers for supplying ink thereto when the first roll-

ers are lifted; and an adjusting screw in said lever bearing against the underside of said plate.

6. Means for intermittently advancing a strip longitudinally, a platen slidable toward and from the strip, a plurality of separate plates in a pack at one side of the strip, a follower plate for sliding said plates sequentially toward and away from said platen, a pair of inking rollers between said pile of plates and said platen, vertical posts supporting said inking rollers, a horizontal plate surrounding said posts, a lever extending under said plate, a shaft, a cam thereon for rocking said lever to reciprocate said posts and lift the ink rollers intermittently, a distributing roller above said ink rollers for

supplying ink thereto when the first rollers are lifted, an adjusting screw in said lever bearing against the underside of said plate, 20 a sliding roller above the distributing roller, a grooved collar carried by the shaft of the sliding roller, a pivoted lever engaging said grooved collar, a cam engaging said lever to rock the same and slide the sliding roller, 25 and means for operating said cam.

In testimony whereof, I have hereunto set my hand at Los Angeles, California, this 23rd day of June 1909.

ELIJAH A. OVENSHIRE.

In presence of—

G. T. HACKLEY,
FRANK L. A. GRAHAM.
